COMBINATION FREEZER AND REFRIGERATOR
CABINET OR SIMILAR ARTICLE

Jean O. Reinecke, Oak Park, Ill., assignor to Amana Re-
frigeration, Inc., Amana, Iowa, a corporation of Iowa

Application September 6, 1955, Serial No. 37,801

Term of patent 14 years

(Cl. D67—3)

FIG. 1.

FIG. 1.

FIG. 2.

Figure 1 is a perspective view of a combination freezer and refrigerator cabinet or similar article showing my new design;

Figure 2 is a front elevation thereof;

Figure 3 is a side elevation thereof.

The dominant features of my design reside in the portions shown in full lines.

I claim:

The ornamental design for a combination freezer and refrigerator cabinet or similar article, substantially as shown and described.
